David Wooster of China, State of New York.

Letter Patent

The schedule referred to in these Letters Patent and making part of the same, containing a description in the words of the said David Wooster himself of his improvement in manufacturing Brooms or Brushes,

To all persons to whom these presents shall come David Wooster of the town of China in the County of Genesee, aine State of New York, sends greeting.

Be it known that I the said David Wooster have invented a new and useful improvement not known or used before, in the making or manufacturing of brooms, or brushes, which invention & the manner of using it is as follows. Take two pieces of cord, hard leather, or any kind of metal, as long as you wish to have your brush, if wood or leather, let a narrow strip of iron, run the length of one of the pieces, & turn up at each end sufficient to embrace the thickness of the brush. Throw this strip of iron, and attached to it, let there go thro' the centre of the piece, the brush, and the opposite piece, a screw sufficiently long to receive a nut. If desirable there may be a nut & screw at each end the one however thro' the centre will answer every purpose. Let the inside of each piece be ovaling, by which means the brush will be kept more firmly in its place. To the bottom of the handle is fastened a steel spring tho' the lower end of which is a hole to admit the aforesaid screw. & when it comes in contact with the upper piece, it should hang there, so as to form a loop of about three inches, turning down a little at each end, so that it shall enter the piece & remain firmer in its place, if more than one screw be used it can be lengthened sufficiently to be fastened by each. To these may be added a cap of leather or of metal, or the two pieces may be so constructed as to

draw in, & make,

as to form a cap, & the cap may be so constructed as to supersede the necessity of the piece or stamp. The piece however are performed as they unite economy & durability with simplicity in

These form the head of the broom or brush, & it will be perceived that it can be taken apart at pleasure. Therefore when ever a broom or brush is to be made, take the materials, whether corn, splint, bristle or any other substance which can be used in making or manufacturing brooms or brushes, lay them upon the under piece then upon the upper piece & upon that, fast the handles, then dress on the out or ends, & the broom or brush is complete.

The benefit resulting from this invention is durability, economy, simplicity & in using the brooms or brushes arising from the elasticity occasioned by the spring.

For witness whereof I have hereunto subscribed my name this fourth day of December eighteen hundred and forty eight

Witness,

Geo. W. Say 3
